Des. 234,954
Patented Apr. 22, 1975

234,954

WATER CLOSET

Donald C. Schrock, 1013 N. West St.,
Nevada, Mo. 64772

Filed June 21, 1973, Ser. No. 372,452

Term of patent 14 years

Int. Cl. D23—02

U.S. Cl. D23—65

Fig. 1.

Fig. 2.

Fig. 3.

T19.4.

T19.5.

FIG. 1 is a top plan view of a water closet showing my new design;

FIG. 2 is a front elevational view thereof;

FIG. 3 is a rear elevational view thereof;

FIG. 4 is a side elevational view thereof; and

FIG. 5 is a side elevational view taken from the side opposite that shown in FIG. 4.

I claim:

The ornamental design for the water closet, substantially as shown.
